TIE RACK

Harold Heisler, Chicago, Ill., assignor to Kluson Manufacturing Company, Chicago, Ill., a corporation of Illinois

Application February 11, 1949, Serial No. 75,816

10 Claims. (Cl. 211—101)

1

This invention relates to devices of the nature of necktie-holding racks and may be adapted for sundry uses in a variety of obvious modifications. For example, and purely by way of illustration, the invention can readily be embodied in the form of a towel rack; and, in fact, is susceptible of numerous analogous applications; as presently will be made apparent.

The primary object of this invention is to provide a rack of the above-indicated character adapted for attachment to a wall or the interior of a closet door or other convenient support, comprising an article-supporting arm hinged adjacent the supported end and adapted to be latched in horizontal posture or position and, alternatively, unlatched and lowered to depending posture or position, so that normally the said arm and the articles supported thereby occupy a minimum of otherwise useful space or protrude from the supporting wall or door, as the case may be, to a minimum extent.

A second object is to provide a necktie rack or analogous device conforming to the first-stated object and wherein the article-supporting arm is hinged near its support for both vertical and horizontal rotation; and in this connection it is a further object to provide an arm having a plurality of article-receiving cross-bars spaced apart lengthwise of the arm, including a provision for maintaining the said cross-bars mutually parallel at all times, irrespective of movements of said arm about either its vertical or horizontal fulcrums—the underlying purpose being to render the supported articles highly accessible both for inspection and removal, as well as to render the unloaded cross-bars easily accessible for application of articles thereto.

A third object is to provide a device of the aforesaid character which can be economically manufactured and easily installed, besides being adequately sturdy and not prone to get out of order.

The novel features of this invention can most readily be explained as a part of the ensuing detailed description pertaining to the accompanying drawings wherein is shown a necktie-holding rack constituting one of many practicable embodiments which the invention may assume.

In the drawings:

Fig. 1 is a front view showing the article-supporting arm depending from its supporting bracket—which is the posture to which the arm ordinarily is adjusted;

Fig. 2 is a side view of Fig. 1, likewise showing the arm in depending posture;

2

Fig. 3 is a rear elevational view of the mounting plate;

Fig. 4 is a plan view of the device with the article-supporting arm shown in horizontal posture and swung to one side of center;

Fig. 5 is a fragmentary sectional view showing the article-supporting arm in horizontal posture, and depicting certain details of construction;

Fig. 6 is a section taken at line 6—6 of Fig. 5, showing the bracket construction; and

Fig. 7 is a section at line 7—7 of Fig. 5, showing the manner in which the T-lugs are formed to detachably engage the mounting plate.

The device illustrated comprises a bracket 10 adapted for attachment, as by means of wood-screws or bolts, to a wall or door surface 12 and an arm 14 which is swingable in both the vertical and horizontal planes and is equipped with a number of parallel cross-bars 15 which are designed to receive and support neckties or other articles.

The bracket 10 includes a mounting plate 16, usually of metal, flanged at the edge, as indicated at 16a, to provide clearance space between the back face of the plate and the adjacent mounting surface 12. Said mounting plate 16 is perforated to form two horizontally-spaced vertical slots 17, 17, each having two vertically spaced widened openings 18, 18, for a purpose which presently will be made clear.

Two complementary parallel, horizontally-spaced bracket elements 20 and 21—preferably plastic moldings—are detachably secured to the mounting plate 16 by means of T-lugs 23 formed integrally therewith, each said bracket element having two such lugs spaced apart vertically to match the vertical spacing of the openings 18 in the mounting plate. The heads of said lugs 23 are dimensioned to pass through openings 18 while the necks thereof are sufficiently narrow to enter the narrow portions of the slots 17 and of a length equal to the thickness of the mounting plate plus enough clearance to permit the bracket elements to slide lengthwise of the slots relatively to the mounting plate whereby to effect interengagement between the bracket elements and the mounting plate. Thus, the two bracket elements are firmly supported by the mounting plate and held in predetermined horizontally spaced relation, but are capable of being easily removed from the mounting plate without detaching the mounting plate from its support.

A member 25, preferably a plastic molding, is fitted between the two opposed faces of the bracket elements 20 and 21 and is rotatable in

the vertical plane about a fulcrum pin 26, the two ends of which are seated in circular recesses 38 formed in the respective bracket elements, as most clearly shown in Fig. 6. The member 25 is formed with an integral peripheral tooth 27, Fig. 4, designed to releasably engage an ear 28 which is an integral part of the mounting plate 16 and projects forwardly therefrom for engagement by said tooth for the purpose of latching the arm 14 in horizontal posture. The axial opening or slot 30 in member 25, through which passes the fulcrum pin 26 is elongated in a direction acutely angular to both the vertical and horizontal, Fig. 4, to form an inclined surface in engagement with fulcrum pin 26 so directed that the weight of arm 14 and the load carried thereby is effective to urge the member 25 toward the mounting plate 16, thus tending to prevent inadvertent disengagement of tooth 27 from ear 28 while at the same time not unduly impeding intentional disengagement of those elements.

The arm 14 comprises two parallel, laterally spaced elongate bars 32, 32 of channel cross-section, each pivotally connected by means of a pin 33, 33 to the member 25, and at their outer ends to a tie member 35 by means of pins 34, 34—said tie member forming the outer terminus of the arm.

The cross-bars 15 each consist of a length of stiff wire, bent as shown in Fig. 1; and each of said cross-bars passes through an aperture 36 formed in each of the bars 32, 32—which apertures are elongated lengthwise of said bars 32, as shown in Figs. 2 and 5 so as to permit free movement of arm 14 about the pivotal centers 33, 33.

The neckties or other articles are hung on the cross-bars 15 at either side of arm 14; and said arm normally depends from bracket 10, as depicted in Figs. 1 and 2, in which position it presents a minimum degree of obtrusiveness. Thus, the device is well adapted for mounting on the inside of a closet door, for example, where it might otherwise be objectionable on account of interference with articles of clothing hanging in the closet, when the closet door is closed. It will be self-evident that the adaptability of arm 14 to adjustment into depending posture is advantageous in many situations where space is at a premium and not solely in those cases where the device is mounted in a clothes closet or on the inside of a closet door.

The arm 14 is swingable upwardly about the fulcrum pin 26 from its depending posture to the horizontal posture in which it is depicted in Figs. 4 and 5; and such movement is, of course, accompanied by corresponding rotation of member 25. When said arm has reached horizontal posture, the tooth 27 is in a position to engage ear 28, as shown in Fig. 5, and will become latchingly engaged therewith, upon member 25 being urged toward the mounting plate. The necessary movement of member 25 transversely of the pin 26 to accomplish latching interengagement between ear 28 and tooth 27 is facilitated by the elongation of opening 30, Fig. 5. It may be observed that the elongation of opening 30, Fig. 5, could as well be in the horizontal direction so far as the latching and unlatching of the arm is concerned, but it is preferable that the elongation be inclined, as shown, so that the force acting downwardly on the arm, when in horizontal posture, will set up a component which is effective to bias the member 25 toward the mounting plate, for the reason previously explained. When

the arm 14 has been raised to horizontal posture, it can be swung in the horizontal plane in either direction from center about the pivots 33, 33; and when the arm is thus swung from side to side the cross-bars 15 remain mutually parallel. It will be clear from inspection of Fig. 4, that by swinging the arm 14 to one side or the other, the neckties or other articles hanging on the cross-bars are spread out so that they are readily visible individually and easily accessible for removal. And, conversely, the empty cross-bars are more easily observable by a person facing the rack from the front when the rack is swung to one side.

15 The cross-bars 15 are shown of suitable length for reception of neckties. If the rack is to be used for towels or other articles requiring more space than neckties, the cross-bars should be made proportionately longer.

20 The arm 14 can be lowered from the horizontal posture in which it is shown in Figs. 4 and 5 to the depending posture in which it is shown in Figs. 1 and 2 by pulling the arm outwardly away from the mounting plate so as disengage the tooth 27 from the ear 28. This can be done most readily by lifting the arm slightly while pulling outwardly thereon.

25 It will be apparent that there are many possible modifications within the broad purview of my inventive concept, and, accordingly, I do not wish to be limited otherwise than as indicated by the terms of the appended claims.

What is claimed is:

30 1. A rack of the class described, comprising: a bracket adapted for attachment to a vertical supporting surface, an arm hinged at one end to said bracket for rotation in a vertical plane, said arm including two parallel laterally spaced bars extending from said bracket and each hinged at the bracket end to enable rotation thereof in a horizontal plane when said arm is positioned horizontally, means for releasably latching said arm in a horizontal position, and a plurality of cross-bars carried by said arm and spaced apart lengthwise of said arm and projecting laterally therefrom, said cross-bars each extending transversely of said arm and each loosely connected to the two parallel laterally spaced bars.

35 2. A rack in accordance with claim 1 wherein said cross-bars pass through apertures formed in said parallel bars, said apertures being large enough, lengthwise of said parallel bars, to enable free rotational movement of said parallel bars in a horizontal plane, when said arm is positioned horizontally.

40 3. A rack in accordance with claim 1 including a tie member to which said parallel bars are each pivotally connected at spaced points, said tie member being located remotely from said bracket.

45 4. A rack of the class described, comprising: a mounting plate adapted for attachment to a wall surface, said mounting plate having a forwardly projecting ear, a pair of forwardly projecting parallel bracket elements carried by said mounting plate and spaced apart horizontally in opposed relation, a member disposed between said bracket elements and having pin and slot means for rotation in a vertical plane, said member being bodily movable to a limited extent transversely of its axis of rotation and having a radially projecting tooth adapted to latchingly engage said ear when said member is moved toward said mounting plate, and unlatched from said ear when said member is moved away from said

mounting plate, and an arm carried by and extending outwardly from said member and rotatable therewith in a vertical plane, said arm being hinged adjacent said member for rotation in a plane perpendicular to the plane of rotation of said member, said tooth and ear being operative conjointly to releasably latch said member in the angular position which corresponds to a horizontal position of said arm.

5. A rack according to claim 4 wherein said arm comprises two parallel laterally spaced bars each hinged to said member for rotation in said perpendicular plane and including a plurality of cross-bars extending transversely of said arm and spaced apart therealong, said cross-bars each being loosely connected to each of said parallel bars.

6. A rack of the class described, comprising: a mounting plate adapted for attachment to a wall surface, said mounting plate having two vertical, horizontally spaced slots, a pair of bracket elements, each having one or more rearwardly projecting T-lugs extending through one of said slots and releasably securing its bracket element to said mounting plate, said slots each having at least one widened area for enabling disengagement of said lugs and their respective bracket elements from said mounting plate, said bracket elements being spaced apart horizontally in mutually opposed relation, a fulcrum pin bridged between said bracket elements and supported thereby, a member disposed between said bracket elements and fulcrumed on said pin for rotation in a vertical plane, an arm carried by said member and projecting outwardly therefrom, said arm being rotatable in a vertical plane, together with said member, from a horizontal position to a depending position and vice-versa, and latch means for releasably retaining said arm in horizontal position.

7. A rack in accordance with claim 6, wherein said arm comprises two parallel laterally spaced bars each hinged at one end to said member for rotation in a plane perpendicular to said vertical plane, said bars each being pivotally connected at their distal ends to a tie member bridging said ends, said parallel bars each having a plurality of apertures spaced apart lengthwise thereof, and a plurality of cross-bars extending transversely of said arm and each passing through one of the said apertures in each of said parallel bars, said apertures being elongated lengthwise of their respective bars to enable said parallel bars to shift lengthwise mutually, without interference from said cross-bars when said arm is rotated in said perpendicular plane.

8. A rack in accordance with claim 6, wherein said latch means comprises a forwardly projecting ear on said mounting plate and a radially projecting tooth on said member adapted to engage said ear and thus retain said arm against downward rotation from horizontal posture, said member having an elongated slot engaging said pin whereby said member is bodily movable per-

pendicularly to its axis of rotation to effect engagement and disengagement between said tooth and said ear.

9. A rack of the class described, comprising:
 5 a mounting plate adapted for attachment to a wall surface, a pair of complementary bracket elements attached to said mounting plate and projecting outwardly therefrom in horizontally spaced opposed relation, said mounting plate having an outwardly projecting ear disposed between said bracket elements, a fulcrum pin bridged between said bracket elements and supported thereby, a member disposed between said bracket elements and having an axial opening traversed by said fulcrum pin, an arm carried by said member and extending outwardly therefrom, said arm being rotatable with said member in a vertical plane between a horizontal position and a depending position, said member having a radially projecting peripheral tooth adapted to latchingly engage said ear and thereby releasably retain said arm in horizontal position, said opening being laterally elongated so as to present an inclined camming surface to said fulcrum pin when said arm is in horizontal position, the inclination of said surface being so directed that a downward force on said member is effective to urge said member toward said mounting plate when said arm is in horizontal position,
 20 thereby moving said tooth into a position to latchingly engage said ear, said arm being releasable for movement to depending position by tension applied thereto while in horizontal position.
 25 10. A rack in accordance with claim 9 wherein said arm comprises two parallel laterally spaced bars each hinged at one end to said member for rotation in a plane perpendicular to said vertical plane, a tie member pivotally connected to and bridged between the distal ends of said bars and a plurality of cross-bars spaced apart lengthwise of said arm and carried thereby and extending transversely thereof and loosely connected to said bars, said cross-bars each extending laterally from said arm at opposite sides thereof.
